United States Patent

Des. 242,325

Patented Nov. 16, 1976

242,325

MULTIPLE BOTTLE CARRIER OR THE LIKE

Robert Charles Olsen, Streamwood, Ill., assignor to Illinois Tool Works Inc., Chicago, Ill.

Filed Jan. 31, 1975, Ser. No. 545,857

Term of patent 14 years

Int. Cl. D9—99

U.S. Cl. D9—178

Fig. 1

Fig. 2

Fig. 3

FIG. 1 is a plan view of a multiple bottle carrier or the like showing my new design;

FIG. 2 is a side elevational view; and

FIG. 3 is an end elevational view thereof.

I claim:

The ornamental design for a multiple bottle carrier or the like, as shown.
